(57) **CLAIM**

I claim the ornamental design for tooling for a blow molding apparatus, as shown and described.

DESCRIPTION

FIG. 1 is a perspective view of tooling for a blow molding apparatus showing the new design.

FIG. 2 is a front view thereof.

FIG. 3 is a rear view thereof.

FIG. 4 is right side view thereof.

FIG. 5 is a left side view thereof.

FIG. 6 is a top view thereof.

FIG. 7 is a bottom view thereof; and,

FIG. 8 is a cross-sectional view thereof taken along line "8-8" of FIG. 6.

In these drawings, the solid lines illustrate the claimed ornamental design, whereas the broken lines illustrate portions of the tooling for a blow molding apparatus that form no part of the claimed design.
